SELECTIVE MULTIPLE FEED DEVICE FOR
ROLLING MILLS

James H. Morrison, Pittsburgh, and Harry J. Gehring, Charleroi, Pa., assignors to Pittsburgh Steel Company, Pittsburgh, Pa., a corporation of Pennsylvania

Application October 7, 1940, Serial No. 360,028

6 Claims. (Cl. 86—43)

The invention relates to rolling mills, and more particularly to feed means for feeding heated bars from a heating furnace selectively to any one of three or more entry positions of a hot rolling mill.

During a certain stage in the manufacture of wire, and particularly steel wire, bars which may be approximately 1½" to 2" square and some 30 feet in length are entered into a heating furnace. When heated to the proper hot rolling temperature the bars are discharged one by one from the heating furnace to the first grooved roll stand of a series of roll stands of a hot rolling mill, in which mill the bars are reduced to rods.

The rolls of each roll stand ordinarily have three or more sets of grooves formed therein for carrying out the rolling operation, and such roll stands and the drives therefor are strong enough to simultaneously roll and reduce bars in all of the grooves thereof at one time. However, in all prior constructions known to us, no means has ever been available for feeding bars from the single discharge location of the heating furnace to more than two sets of roll grooves, with the result that the maximum rolling done by any one stand of rolls at any one time has been two bars part of the time and one bar the remainder of the time.

This situation has existed in the operation of hot bar mills for nearly forty years, and has restricted the productive output of all hot rod mills operated, because the available feed means, such as illustrated in Patents Nos. 653,507 and 740,418, could not feed more than two bars alternately one at a time to two sets of grooves or the first or entry roll stand of hot rod mills.

In other words, the feeding devices for existing hot rod mills constitute the bottle neck limiting the productive capacity of existing rod mills in the steel industry.

It is accordingly a primary object of the present invention to provide means for materially increasing the productive capacity of existing hot rod mills.

It is also a primary object of the present invention to materially increase the potential productive capacity of rolling mills, by associating and combining an improved feeding device with existing furnaces and mills, without requiring the slow and expensive installation of additional mills and furnaces.

It is a further object of the present invention to provide a feeding device for a rolling mill, which will feed a bar or the like from a single discharge station of a heating furnace to any 50 55

open one of a plurality of three or more roll entry positions, selectively at will, irrespective of the presence of other bars extending from portions of the furnace to any or all of the remaining roll entry positions.

It is also an object of the present invention to provide a feeding device for a rolling mill which will enable more than two bars or the like to be successively fed from a single discharge station 10 of a heating furnace to be simultaneously rolled on a rolling mill.

Likewise, it is an object of the present invention to provide an improved selective feeding device for a rolling mill, which is simple and inexpensive to install and which may be readily and easily operated by any operator familiar with the operation of hot rod mills and the like.

These and other objects may be obtained and the prior art difficulties overcome by the devices, 20 constructions, arrangements, combinations, parts, elements and apparatus which comprise the present invention, the nature of which is set forth in the following general statement, a preferred embodiment of which is set forth in the following 25 description, and is shown in the drawings, and which are particularly and distinctly pointed out and set forth in the appended claims forming part hereof.

The nature of the improved apparatus of the 30 present invention may be stated in general terms as including in a feed device for feeding bars or the like successively from a single discharge station of a heating furnace selectively to any one of a plurality of three or more roll entry positions, a feed table, combined raising and guide baffle or blade means mounted in operative relation with respect to the table, means for selectively or simultaneously operating any one or more of said baffle or blade means to raise or lower the same, and said baffle or blade means including a baffle or blade located in front of each roll entry position directed toward each other roll entry position of a roll stand having three or more entry positions.

40 45 By way of example, a preferred embodiment of the improved apparatus is illustrated in the accompanying drawings forming part hereof in which

Figure 1 is a diagrammatic view of a hot rod mill and heating furnace therefor equipped with the improved selective multiple feed device;

Fig. 2 is an enlarged plan view of the improved feed device showing parts of the furnace and first roll stand in section;

Fig. 3 is a side elevation with certain parts in

section of the apparatus illustrated in Fig. 2;

Fig. 4 is a top plan view similar to Fig. 2, illustrating some of the feed device operating mechanism;

Fig. 5 is a front elevation with parts in section of some of the apparatus illustrated in Fig. 4;

Fig. 6 is an enlarged view illustrating one operative position of the improved feed device;

Fig. 7 is a sectional view taken on the line 1—1, Fig. 6;

Fig. 8 is an enlarged view similar to Fig. 6, showing a second operative position of the improved feed device;

Fig. 9 is a section taken on the line 9—9, Fig. 8;

Fig. 10 is a view similar to Figs. 6 and 8 showing a third operative position of the improved feed device; and

Fig. 11 is a section taken on the line 11—11, Fig. 10.

Similar numerals refer to similar parts throughout the various figures of the drawings.

In the drawings, a bar heating furnace is illustrated generally at 12 and may include a heating hearth 13. Bars enter the furnace 12 one by one from a station 14 and are pushed by pusher means 15 to a single discharge station 16, from which location they are pushed one by one by pusher means 17 endwise through furnace exit door 18 to the improved feed device generally indicated at 19.

The improved feed device 19 feeds the bars selectively to any one of three operative positions of the first stand of grooved rolls 20 of a hot bar mill generally indicated at 21, which may include a usual number of successive roll stands after the initial or entry roll stand 20. The bars are rolled and reduced on the bar mill 21 in accordance with usual practice to form rods or the like, and are then coiled on reels in the usual manner for further desired treatment.

The rod mill 21 and bar heating furnace 12 may be of any usual or well known construction, and the present invention deals more particularly with the improved selective feed device generally indicated at 19 and its cooperative and coordinated location and arrangement with respect to the heating furnace and the rod mill.

As shown, the rolls of each roll stand are provided with three grooves marked X, Y and Z, and the entry roll stand 20 is provided with an entry box 22 having passages 23, 24 and 25 leading respectively to grooves X, Y and Z. The improved feed device 19 includes a feed table 26, on which outer stationary guide brackets 27, 28 and 29 are mounted.

A plurality of raising and guide baffles, plates or blades A, B, C, D and E are movable in and extend upwardly through staggered slots provided therefor in the feed table 26 and extend angularly in one direction or another with respect to a longitudinal center line passing through the rolling mill 21 and furnace door 18. As shown, the slots for plates A, C and D are parallel to each other and are all angled in the same direction; the slots for plates B and E are parallel to each other and are all angled in the same direction; and the slots for plates B and E are angled in a different direction from the slots for plates A, C and D.

These guide baffles may be individually or independently moved with respect to the feed table or raised and lowered between a position or location in which their top surfaces are flush with the top surface of the feed table, and a position or location in which their top surfaces are pro-

jected or located above the top surface of table 26 a greater distance than the maximum cross sectional dimension of any bar being fed from the furnace 12 to rolling mill 21 by the feed device 19.

The raising and lowering of guide baffles A, B, C, D and E may be effected by any suitable means as by pivotally connecting the lower ends thereof as at 30 (Fig. 5) to levers 31, one end of each of which is pivotally connected at 32 to brackets 33 mounted on the underside of feed table 26. The other end of each lever 31 may be provided with a counterweight 34 and with a raising line such as a chain 35 extending up and around a sheave or pulley 36 mounted on a bracket 37 on the roof of furnace 12. The chains 35 are connected respectively to piston rods 38 of hydraulic cylinders 39, the operation of which may be controlled by suitable valves (not shown) conveniently located for operation by an operator who ordinarily stands beside the feed device 19 and furnace exit door 18.

As shown, one of cylinders 39 (Fig. 3) by an inverted Y chain connection, may operate baffles A and D simultaneously. For convenience, small letters a, b, c, d and e have been placed on Fig. 3 below the lever assemblies respectively for operating baffles A, B, C, D and E.

The bars being heated in heating furnace 12 are generally indicated by the numeral R, and referring to Figs. 1 and 6 to 11, inclusive, a bar being entered (Figs. 6 and 7) into roll groove X is indicated RX, a bar being entered into roll groove Y (Figs. 8 and 9) is indicated RY, and a bar being entered into roll groove Z (Figs. 10 and 11) is indicated RZ.

In Figs. 6 and 7, the bar RX being entered into groove X is shown in full lines, and the locations of bars RY and RZ, which may have been entered into grooves Y and Z, are shown in dot-dash lines. Similarly, in Figs. 8 and 9, the bar RY being entered into groove Y is shown in full lines, and the locations of bars RX and RZ being rolled in grooves X and Z are shown in dot-dash lines. Also, in Figs. 10 and 11, bar RZ, being entered into groove Z, is shown in full lines and the locations of bars RX and RY being rolled in grooves X and Y are shown in dot-dash lines.

Bars RX, RY and RZ are all pushed out of furnace 12 from the same location or station 16, and by means of the improved feeding device, one or a plurality of the bars moving from the furnace through the rolls may be raised to permit a third bar to be passed underneath the rear portions of the other two bars into any one of the three grooves X, Y or Z, whichever happens to be open.

To accomplish this, a bar passing along the position shown by RX may be raised by guide baffle B; a bar passing along the location indicated by RY will be raised by either guide baffle C or E; and a bar passing along the location indicated by RZ may be raised by guide baffles A and D. Bar RX is guided into groove X by guide plates A and C and also stationary guides 28 and 29. Bar RY is guided into groove Y by guide plates A, B and D. Bar RZ is guided into groove Z by guide plates B and E and stationary guide 27.

Stationary guide projections 40 and 41 may also project upwardly from feed table 26 to continue defining channels 23, 24 and 25 formed by entry box 22.

The improved feed device may operate typically as follows:

A first bar RX pushed out of furnace 12 may

be fed to groove X by having previously raised guide plates A and C (Fig. 6). Immediately, guide plate B is raised, guide plates A and C are lowered, and guide plate E may be raised to feed a second bar RZ into groove Z (Fig. 10). Bar RZ necessarily must pass underneath the rear portion of bar RX, which is not yet out of furnace 12, because all of the bars are pushed from the same general location 16 of the furnace.

Now, with guide plate B still raised, guide plates A and D are raised and guide plate E is lowered, thus raising the rear portions of both bars RX and RZ up so that another bar RY may be fed from the furnace into the center groove Y (Fig. 8). Thereafter, it makes no difference which bar groove X, Y or Z first becomes free, because by manipulation of guide plates A, B, C, D and E, the next bar from the furnace can be immediately entered into any one of the three grooves X, Y and Z.

Thus, the mill illustrated, can roll two bars all of the time in the three groove roll stands with three bars being rolled substantially all of the time. As a result, in actual operation, a mill which had been operated for many years with a maximum production of approximately 43,000 pounds per hour, was immediately operated with a production of more than 53,000 pounds per hour by the addition of the improved feed device.

The essential conditions of the improved feeding device are that there is at least one angled raising and guide plate in front of each roll groove directed toward each other roll groove. Guide plate B in front of groove X is directed toward both grooves Y and Z; guide plate C in front of groove Y is directed toward groove X; guide plate E in front of groove Y is directed toward groove Z; and guide plates A and D in front of groove Z are directed toward grooves X and Y. The guide plates therefor when moved upward provide means for raising or lifting upward from the table the rear end of any bars being rolled in any grooves and for directing the entry of another bar into any other groove of a mill having at least three grooves; and the guide plates when moved downward, are in a non-lifting and non-guiding location.

The improvement is not limited to rolling on 50 roll stands having three grooves or passes because by substantially duplicating the construction for say four, five or six grooves, in which duplicated construction there are raising and guide plates in front of each groove which cut off the entry into that groove and direct the entry to any one of the other grooves, four, five or six strands or bars can be rolled simultaneously at one time.

Moreover, the invention is not limited to the 60 rolling of bars or rods on a hot bar mill, because the same device can be used on a wide strip mill for feeding three or more narrow strip strands at one time, and can be also used for feeding three or more ovals, rectangles, squares, flats or tube rounds to a mill for reducing the same.

Having now described the features of the invention, the construction, operation and use of a preferred embodiment thereof, and the advantageous, extraordinary and heretofore unattainable results attained by the improved construction; the new and useful parts, elements, combinations, constructions and devices, and reasonable mechanical equivalents thereof obvious to 70 75

those skilled in the art, are set forth in the appended claims.

We claim:

1. Apparatus for feeding bars and the like successively from a heating furnace selectively to any one of a plurality of three or more rolling mill entry positions, including a feed table, a plurality of baffle plates movable between locations with their top surfaces flush with the top

10 surface of said feed table and locations with their top surfaces projected above the top surface of said feed table, means for selectively raising and lowering any one or more of said baffle plates with respect to the table, each of said baffle 15 plates being located in angular relation with respect to the line of travel through said rolling mill, and there being at least four baffle plates with at least two differently angled baffle plates located in front of at least one mill entry position, each of said baffle plates being adapted to direct one bar toward a certain mill entry position while raising another bar already passing through another mill entry position above the level of said one bar.

25 2. Apparatus for feeding bars and the like successively from a heating furnace selectively to any one of three rolling mill entry positions, including a feed table, a baffle plate mounted on the feed table in front of the first rolling mill entry position directed toward the second and third said positions, a baffle plate located in front of the second rolling mill entry position directed toward said first position, a baffle plate located in front of said second rolling mill entry position 35 directed toward said third position, at least one baffle plate located in front of the third rolling mill entry position directed toward the first and second said positions, and means for raising or lowering any one or more of said baffle plates to 40 selectively raise one or more bars being rolled by the mill and direct and guide another bar to any third remaining open roll entry position.

3. Apparatus for feeding bars and the like successively from a heating furnace selectively to any one of a plurality of three or more rolling mill entry positions, including a feed table provided with a plurality of staggered slots, at least one of said slots being angled in the same direction as another slot, at least one of said slots being angled in a different direction from another slot, and all of said slots being angled with respect to the line of travel through said rolling mill; baffle means including a plate movable upward in each of said slots to a location projecting above said table for lifting one or more bars being rolled by the mill upward from the table and for directing and guiding another bar selectively to any third remaining open roll entry position, each plate being also movable downward to a non-lifting and non-guiding location; and means for selectively moving any one or more of said plates to either of said locations.

4. Apparatus for feeding bars and the like successively from a heating furnace selectively to any one of a plurality of three or more rolling mill entry positions, including a stationary feed table; baffle means mounted for movement with respect to the feed table and adapted to be projected above the top surface of said table, said baffle means including at least one angled plate located in front of each of at least three roll entry positions directed toward each other roll entry position, and said plates being movable downward to a non-lifting and non-guiding location; and means for selectively raising and

lowering the plates for raising bars being fed through one or more entry positions and directing another bar toward a third entry position.

5. Apparatus for feeding bars and the like successively from a heating furnace selectively to any one of a plurality of three or more rolling mill entry positions, including a stationary feed table provided with stationary guide means projecting upwardly from the table to define channels leading to each rolling mill entry position; baffle means mounted for movement with respect to said table, said baffle means including at least one angled plate located in front of each channel directed toward each other channel, said plates being movable independently of each other to locations projecting above the top surface of the feed table for selectively blocking off any of said channels, for lifting upward from the table any bar traversing the feed table and extending along the channel so blocked off, 10 and for directing the forward end of another bar traversing the feed table into another channel;

and means for selectively moving any one or more of said plates to raise or lower the same with respect to the feed table.

5 6. Apparatus for feeding bars and the like successively from a heating furnace selectively to any one of a plurality of three or more rolling mill entry positions, including a feed table, baffle means mounted for movement with respect to the table, said baffle means including at least one angled plate located in front of each of at least three roll entry positions and directed toward each other roll entry position, and means for selectively moving any one or more of said plates to raise the same to a bar lifting and guiding position and to lower the same to a non-lifting and non-guiding position, each of said baffle plates being adapted to direct one bar toward a certain mill entry position while raising another bar already passing through another mill entry position above the level of said one bar.
